SUCTION CLEANER

Donald G. Smellie, Canton, Ohio, assignor to The Hoover Company, North Canton, Ohio, a corporation of Ohio

Application June 27, 1938, Serial No. 216,072

19 Claims. (Cl. 15—6)

The present invention relates to suction cleaners in general and particularly to a new and novel agitating means in a suction cleaner. Specifically the invention comprises a suction cleaner in which surface agitation is accomplished by reciprocating beating and brushing elements which are actuated by new and novel means.

It is an object of the present invention to provide a new and improved suction cleaner. It is another object of the invention to provide a suction cleaner incorporating new and improved surface-agitating means. It is another object of the invention to provide a suction cleaner having new and improved agitator-actuating means. A still further object of the invention is to provide a suction cleaner in which the rotating force of the driving motor is transformed into reciprocating force at the agitating elements by a new and improved conversion mechanism. A still further object of the invention is to provide, in a suction cleaner, a reciprocating agitator which is driven by a rotating force and which is so mounted as to transmit a minimum of vibration to the remainder of the cleaner. A still further object of the invention is to provide a suction cleaner in which surface agitation is accomplished by a vertically reciprocating beating element and an arcuate rotary brushing element. These and other more specific objects will appear upon reading the following specification and claims and upon considering in connection therewith the attached drawings to which they relate.

Referring now to the drawings, in which preferred embodiments of the present invention are disclosed:

Figure 1 is a side elevation of a cleaner constructed in accordance with the present invention, a section being shown through the cleaner nozzle and agitating means upon the line 1—1 of Figure 2;

Figure 2 is a partial bottom view of the cleaner shown in Figure 1;

Figure 3 is a section upon the line 3—3 of Figure 2 and shows one of the brush-supporting bearings;

Figure 4 is a section upon the line 4—4 of Figure 2 and shows the brush-actuating linkage;

Figure 5 is a longitudinal section through the agitator, being taken upon the line 5—5 of Figure 2;

Figure 6 is a transverse vertical section through the agitator upon the line 6—6 of Figure 5;

Figure 7 is a section upon the line 7—7 of

Figure 5 and illustrates the eccentric relationship of the beating element supporting shaft in the driving pulley;

Figure 8 is a section upon the line 8—8 of Figure 5 and also illustrates the connecting means between the reciprocating rigid agitator and the oscillating brushing element;

Figure 9 is a side elevation of a cleaner embodying the second modification of the invention, a section being shown through the cleaner nozzle upon the line 9—9 of Figure 10;

Figure 10 is a partial bottom view of the cleaner illustrated in Figure 9;

Figure 11 is a section through the agitator upon the line 11—11 of Figure 10;

Figure 12 is a section through the brush-actuating means upon the line 12—12 of Figure 10;

Figure 13 is a longitudinal section through the agitator upon the line 13—13 of Figure 10;

Figure 14 is a section upon the line 14—14 of Figure 13 and illustrates the agitator-mounting means;

Figure 15 is a section upon the line 15—15 of Figure 13 and illustrates the eccentric relationship of the center of mass of the rotary weight to its supporting shaft;

Figure 16 is a section upon the line 16—16 of Figure 10 and shows the jack shaft and wheel-supporting structure.

In the modern suction cleaner the cleaning of surface coverings is accomplished by the combined action of surface agitation, which dislodges the foreign material from the surface covering, and air flow which removes it. Reciprocating agitating means have certain advantages and certain disadvantages as well. Among the important advantages is the fact that an agitating blow may be struck the surface covering at any desired angle or relationship with an entire absence of rubbing contact if desired. Among the disadvantages is the fact that the reciprocating forces of the agitating means is usually transmitted directly to the cleaner body resulting in undesirable vibrations and noise. In the suction cleaner constructed in accordance with the present invention the surface agitation is accomplished by a reciprocating agitator which is actuated by a new and novel mechanism, the agitator being so mounted that there is a minimum of vibration transmitted to the supporting cleaner structure.

The first embodiment of the invention, illustrated in Figures 1 to 8, inclusive, of the drawings, includes a main casing having a nozzle 1, a fan chamber 2, connected to the nozzle 1 by

an air passageway 3, and an exhaust outlet 4 to which is removably attached a dust bag 5. Surface-contacting front and rear lips 6 and 7 define the nozzle mouth. A motor casing 8 is positioned upon the main casing immediately above the fan chamber 2 and houses an unknown driving motor, the shaft 9 of which extends downwardly through the fan chamber 2 and into the air passageway 3, being formed in the latter as a pulley surface 9 and supporting in the former the suction-creating fan 10. A pivoted handle 11 provides means by which the operator may readily propel the cleaner over a surface covering to be cleaned, the entire cleaner being carried by front and rear supporting wheels 12 and 13, respectively. As in the usual cleaner, nozzle-height-adjusting means, indicated generally by the reference character 14, are provided by which the rear wheels 13 may be raised and lowered relative to the cleaner body for the purpose of pivoting the nozzle about the front wheels 12, 12 and so raising or lowering it relative to the surface covering undergoing cleaning. Also, in the manner common to suction cleaners, a handle position control detent 15 of the roller type is provided which is spring-pressed into contact with means carried by the handle to retain the handle in certain positions and within certain ranges of movement.

Positioned within the nozzle 1, and adapted to contact a surface covering undergoing cleaning between the nozzle lips 6 and 7, are aligned elongated rigid beater elements 20, 20 which are rounded at their surface-contacting portions and which are mounted upon the opposite ends of a rigid non-rotating shaft 21. Each beater element 20 is provided at its outer end with a guide pin or element 22 which slidably seats within a vertical guideway 23 formed on the end wall of the nozzle. The supporting shaft 21 of the beater elements 20, 20 is itself carried by the inner race of a ball bearing 25 which is eccentrically positioned within a rotatable pulley 26 of relatively great mass. The eccentricity of the bearing 25 and shaft 21 relative to the true center of the pulley is indicated by the distance "E" in Figures 5 and 7. The pulley 26 is formed at its sides with counterbored peripheral rims 27, 27, each of which provides a seat for the outer race of a sealed supporting bearing 28, the inner race of which seats upon a cylindrical metallic sleeve 29 enclosing the supporting shaft 21 in spaced relationship. A radially extending flange 30 upon the surface of each sleeve 29 cooperates with a pulley rim-carried cup 31 to provide a bearing-protecting labyrinth seal exteriorly of the adjacent ball bearing 28 to prevent the entrance into the bearing of foreign material which is always present within the cleaner nozzle.

Each pulley-supporting sleeve 29 resiliently supports the inner end of a rigid hollow agitator body element 33 by a flexible resilient connecting sleeve 34 of rubber or similar material, the body 33 being resiliently supported at its outer end by an end-wall-carried resilient rubber mounting 35. Clamping metallic bands 36 and 37 secure each flexible sleeve 34 upon the ends of the sleeve 29 and body element 33, respectively, while the interior end of each rubber mounting 35 seats directly within the cylindrical open end of the body element 33 and has its outer end seated within a nozzle-wall-carried socket 38. The supporting mountings 35, 35 and the connecting sleeves 34, 34 are of such resiliency and strength that the entire agitator comprising the rotatable

5 pulley, the beating elements eccentrically carried thereby, the sleeves 29, 29 and the body 33, 33 are supported within the cleaner nozzle for relatively free movement within limits in any given direction. The movement of the agitator is but little interfered with by the spaced positioning springs 39, 39 which are suitably connected to the front wall of the nozzle and to eyes formed in the clamping elements 36, 36. These springs primarily offset the driving tension of the agitator-driving belt 16.

10 Positioned rearwardly of the rigid beating element 20 and extending parallel thereto is an elongated flexible brushing element 40 formed with a rigid bristle-carrying back along its upper side. At each end of the brush is a supporting pin 43 which seats within a wall-carried bearing 44 for rocking movement. A link 41 rotatably encloses the agitator shaft 21 and extends 15 through an opening formed in the enclosing body element 33 to seat pivotally upon a pin 45 carried by the back of brush 40. The link's pivotal mounting upon the brush is above the pivotal axis of the brush as represented by the supporting pins 43, 43 and movement of the link 41 caused by the movement of the agitator shaft 21 results in the arcuate rotary movement or sweep- 20 ing action of the brush 40 upon the surface covering which it contacts.

25 The operation of this first preferred embodiment of the invention is as follows. Upon the machine being placed in operation the unshown motor begins its rotation driving the pulley 9 formed at the lower end of its shaft and also the suction-creating fan 10. The fan 10 creates a reduced pressure within the fan chamber 2 which is effective through the air passageway 3 into the nozzle 1 where the surface covering is lifted upwardly into contact with the lips 6 and 7. The dirt-laden air drawn through the nozzle is exhausted from the fan chamber through the outlet 4 into the filter bag 5. The rotation of the pulley 9 causes the belt 16 to transmit the rotary force thereof to the agitator pulley 26 30 which is resiliently supported within the cleaner nozzle and which eccentrically supports the beater-element-carrying shaft 21. The latter causes the beater element 20 to reciprocate in a vertical plane. As the pulley speed increases and as it approaches its normal speed of rotation it rotates about the true center of mass of the entire rotating system with an absence of gyration. The center of mass of the pulley alone will actually 35 be opposite in eccentricity to the shaft 21 and the parts attached thereto, but as these parts also move about the supporting axis they exert a centrifugal force which the mass of the pulley will exactly counterbalance at the operating speed. Obviously, if the pulley rotates about the true 40 center, the center of shaft 21 must move or gyrate about that true center and in a rotary orbit, its circuit being as indicated in Figure 7 by the circular arrows. This movement is directly transmitted to the beater elements 20, 20 which are prohibited horizontal translation at their lower ends by the vertical guides 23, 23 and which, accordingly, move vertically. The movement of the shaft 21 in its orbit is also effective to pivot the brush 40 upon its pivotal axis, the shaft and the brush being directly connected by the link 41, as aforescribed. In actual operation the agitator body as represented by the rotating pulley 26, the supporting sleeve 29, 29 and the agitator shell 33, 33 remain substantially fixed in 45 position and the springs 39, 39 perform the func- 50 55 60 65 70 75 76

tion of offsetting the tension of the driving belt 16. When the agitator is initially being placed into operation the springs also tend to minimize the vibration of the agitator body.

In operation, therefore, the beater element 20 reciprocates vertically while the agitator body and pulley 26 remain substantially fixed, the movement of the beating element 20 being accompanied by the arcuate rotary movement of the brush element 40. The agitation imparted to the surface covering by the agitating elements dislodges therefrom foreign material which is carried by the air stream through the cleaner and to the dust bag.

The entire agitator including the rigid beating elements and the flexible brush elements are removable from the nozzle upon the removal from the end walls thereof of the screws indicated by the reference characters 46, 46 etc. which extend through the nozzle end walls to secure in place the removable agitator support plates 47, 47 upon each of which is formed the rubber mounting socket 38, the vertical guide 23, and the brush supporting bearing 44.

The second preferred embodiment of the invention is illustrated in Figures 9 to 16, inclusive. The general arrangement of the suction cleaner body is slightly different than in the first embodiment but comprises the same essential parts but which bear different reference characters. The cleaner comprises a nozzle 50 having surface-contacting nozzle lips 51 and 52. Passageways 53 and 54 extend rearwardly from the nozzle, the latter only opening into the nozzle and serving as an air passageway connected to the suction-creating means of the cleaner. The former serves as a belt channel within which is positioned a power-transmitting belt 55 which is connected to a pulley 56 formed upon the extended end of the motor shaft from the motor housing 57. The cleaner casing indicated generally by the reference character 59, houses the suction-creating means and is formed with a rearwardly extending exhaust outlet 60 to which is removably attached a suitable filter dust bag 61. A pivoted handle 62 provides means by which the machine can be propelled over a supporting surface covering upon its supporting wheels 63 and 64, the latter being provided with manually operable height-adjusting means 66 by which they may be raised and lowered relative to the cleaner body for the purpose of adjusting the height of the nozzle 50.

As distinguished from the first embodiment the present embodiment is formed with a belt channel separate from the air passageway leading from the nozzle to the suction-creating means. The belt channel or passageway 53, however, is not open to the nozzle but instead is sealed therefrom and the rotative force of the belt 55 is made available to the nozzle by means of a jack shaft 68 which rotatably supports one of the front wheels 63 and which is itself rotatably supported in ball bearings 69, 69 upon opposite sides thereof. A pulley 71 is carried by the jack shaft 68 within the channel 53 and to it connects the power-transmitting belt 55. Upon the opposite end of the shaft 68 a second pulley 72 is located within a short rearwardly extended passageway 73 open to the interior of the nozzle 50 and seats a second power-transmitting belt 74. The opposite end of the belt 74 seats upon an agitator pulley 76 positioned adjacent one end wall of the nozzle 50 and between the lips 51 and 52. The pulley 76 is

5 mounted upon the extended end of the agitator shaft 77, the shaft ends being eccentrically positioned relative to the main central portion thereof and being rotatably mounted in suitable sealed ball bearings 78, 78 resiliently carried at the nozzle ends.

10 The bearings 78, 78 are resiliently mounted in the nozzle-supported resilient sleeves 80, 80 and, as in the case of the first embodiment, a belt-driving-tension-opposing spring 81 is provided which here contacts the outer race of the bearing 78 carrying the end of shaft 77 upon which the pulley 76 is mounted.

15 The agitator body encloses the major central portion of the shaft 77 and is indicated by the reference character 84 being rotatably mounted upon the shaft 77 by means of bearings 85, 85 at its ends. Body 84 is not of uniform size throughout its length but is instead provided with enlarged sections within each of which is positioned a cylindrical weight or mass 86. Weights 86 are physically concentric with the central portion of shaft 77 but are unbalanced relative thereto by the presence of longitudinal bores 87. The center of mass of the weights 86, 86 lie upon an axis which is diametrically opposite to the central portion of shaft 77 when referred to the axis of rotation. Further, the eccentricity of the axis of the centers of masses is sufficient that the weights counterbalance the forces set up by the shaft 77, the housing 84 and the gyrating portions of the beater element in operation so that the parts move in equilibrium about the axis of rotation. The eccentricity of the rotary axis of shaft 77 relative to its central portion is represented by the letter "E" in Figure 15. The ends of the agitator body 84 are enclosed by the flexible extensions of rubber sleeves 80, 80 which provide enclosures to seal the supporting bearings 78, 78 from the dirt laden air in the interior of the nozzle 50.

20 The rigid beating element 88 is rigidly connected to the agitator body 84 and moves therewith, being provided at its ends with guide pins 89, 89 which slidably seat within vertical guideways 90, 90 formed on the interior walls of the nozzle. Obviously upon the movement of the agitator body 84 in a circular orbit during the rotation of shaft 77, the body being mounted upon the offset central portion of the shaft, the beater element 88 will move vertically, the guide pins 89, 89 sliding within the vertical guideways 90, 90.

25 Rearwardly of the rigid beating element 88 and extended parallel thereto is a brush element 92 which extends the full length of the agitator and is pivotally mounted at its ends rearwardly of the agitator supporting bearings 78, 78 in sleeve bearings 93, 93. A rocker arm 94 rotatably seats upon a reduced portion of the agitator body 84 at one of its ends and pivotally connects to the pivotally mounted brush 92 by rotatably enclosing a brush-carried pin 95. The relationship is such that the gyration of the agitator body 84 causes the brush 92 to be pivoted about its supporting axis to sweep the contacted surface covering. All components of movement in a horizontal plane which are imparted to the arm 94 by the movement of the agitator body 84 results in the pivotal movement of the surface-contacting brush 92 while vertical components of movement imparted to the arm merely result in its being pivoted upon its brush-connected pin 95.

30 The operation of this second embodiment of

the invention is as follows. Upon being placed in operation the cleaner motor drives the suction-creating means to create a reduced pressure within the nozzle 50 which draws cleaning air through the passageway 54 and exhausts it from the cleaner by way of the exhaust outlet 60 into the filter bag 61. The rotation of the motor shaft is transmitted by the intermediate belt 55 to the jack shaft 68 and by the belt 74 to the agitator driving pulley 76. Rotation of the latter causes the agitator shaft 77 to rotate and as the intermediate major portion thereof is offset from the bearing-carried ends thereof the agitator body rotatably mounted thereon by the bearings 85, 85 will gyrate in a circular orbit as indicated by the arrows in Figures 12 and 15.

As the rigid beater element 88 is rigidly carried by the body 84, the gyration of the latter results in the vertical movement of the former which thereupon imparts to the surface covering lifted by the nozzle suction against the surface-contacting lips 51 and 52 a vertical beating action. The spaced weights 86, 86, which have their centers of mass eccentrically positioned relative to the central portion of agitator shaft 77 so that the axis of gyration of the system is aligned with the supporting offset ends of the shaft, rotate as the shaft rotates. These weights are in fact physically concentric with the central portion of shaft 77 but have their centers of mass eccentrically positioned relative thereto through being provided with the bores 87. At high rotational speeds the weights provide a stabilizing force which minimizes the transmission of the vibration forces from the beater element back to the supporting structure of the agitator. The gyration of the agitator body 84 also results in the movement of the rocker arm 94 therewith and the pivotal movement of the brushing element 92, the latter sweeping back and forth across the surface covering contacted with each vertical blow delivered by the rigid beater element 88.

In both embodiments of the invention the resilient supporting means reduces the transference to the cleaner body of small uncancelled and uncompensated vibrations thereby resulting in quieter and smoother cleaner operation.

I claim:

1. In a suction cleaner, a body, a rotatable mass, means resiliently supporting said mass for rotation on said body upon an axis eccentric to the center of mass of said rotatable mass, an agitating element rotatably connected to said rotatable mass eccentrically relative to the axis of rotation of said mass, the eccentricities of said center of mass and said element being oppositely displaced sufficiently to counterbalance in the rotation of said mass at operative speed, and means to rotate said mass at its operative speed.

2. In a suction cleaner, a body, a mass resiliently mounted on said body for rotation about an axis through itself, a beater element rotatably connected to said mass upon an axis eccentric to said first axis, the eccentricity of the center of said mass being at all times opposite to the point of connection of said element thereto so that the center of mass of the system comprising said mass and element lies on the axis of rotation of said mass, means to rotate said mass at an operative speed at which the unbalance of said mass and elements are cancellative, and means to restrict the surface-contacting portion of said element to linear reciprocation upon the gyration of its mass-connected portion.

3. In a suction cleaner, a body, a rotatable

mass, means resiliently and floatingly mounting said mass on said body for rotation about an axis substantially through its center of mass, a beater element having a surface-contacting portion mounted for linear reciprocation, and means supporting said element directly upon said mass eccentrically relative to said axis and adapted to be gyrated upon the rotation of said mass to reciprocate the surface-contacting portion of said element, the eccentricity and mass of said element being such that the unbalance of said rotatable mass is neutralized at operative speeds.

4. In a suction cleaner, a body, a rotatable pulley of relatively great mass, a driving belt seated on said pulley, means resiliently supporting said pulley for rotation upon said body, the center of mass of said pulley being eccentric relative to its axis of rotation, a non-rotatable shaft mounted in said pulley eccentrically of its axis of rotation and adapted to be gyrated upon the rotation of said mass, a beating element mounted upon said shaft, and means to restrict the surface-contacting portion of said element to linear reciprocation.

5. In a suction cleaner, a body, a rotatable pulley of relatively great mass, a driving belt seated on said pulley, bearing means and resilient means supporting said pulley for rotation on said body about an axis eccentric to its center of mass, a non-rotatable shaft supported in said pulley eccentrically relative to its center of mass and at a point spaced diametrically therefrom with respect to the axis of pulley rotation, and a rigid beater element carried by said shaft.

6. In a suction cleaner, a body, a rotatable pulley of relatively great mass, bearing means and resilient means supporting said pulley for rotation on said body about an axis eccentric to its center of mass, a non-rotatable shaft supported in said pulley eccentrically relative to its center of mass and at a point spaced diametrically therefrom with respect to the axis of pulley rotation, a rigid beater element carried by said shaft, a pivotally mounted brush, and means connecting said brush to said shaft adapted to oscillate said brush upon said shaft being gyrated by the rotation of said pulley.

7. In a suction cleaner, a body, an agitator including an eccentric rotary mass resiliently mounted on said body on an axis through the center of mass of the agitator, a shaft supported within said mass eccentrically relative to the center of mass of the agitator and adapted to be gyrated upon the rotation thereof, a rigid beater element connected to said shaft, and means to restrict the movement of the surface-contacting portion of said element to linear movement.

8. In a suction cleaner, a body, an agitator including hollow portions resiliently supported on said body, a pulley of relatively great mass rotatably and resiliently supported by said hollow portions, a driving belt connected to said pulley, a shaft non-rotatably supported by said pulley eccentrically relative to its axis of rotation, the center of mass of said pulley being diametrically displaced upon the opposite side of said axis of rotation from the central axis of said shaft sufficiently to counterbalance said shaft and the parts connected thereto, in the rotation of said pulley at its normal operating speed, and a beater element connected to and actuated by said shaft.

9. In a suction cleaner, a body, a rotatable member, means resiliently supporting said mem-

ber on said body for rotation about an axis through the dynamic mass-center of said member and all elements supported thereby, beating-element-supporting means eccentrically connected to and non-rotatably carried by said member eccentrically relative to said axis and adapted to be gyrated upon the rotation of said member, a beater element connected to said means and actuated thereby, the center of mass of said rotatable member being sufficiently eccentric relative to its axis of rotation as to set up forces at its normal speed of rotation which counterbalance the forces set up by the gyration of said supporting means and the parts attached thereto.

10. In a suction cleaner, a body, a rotatable member resiliently mounted on said body, a non-rotatable beater element connected eccentrically to said rotatable member relative to the axis of rotation thereof, means to guide the surface-contacting portion of said beater element toward and from a surface covering undergoing cleaning, said rotatable member including an eccentric mass so related to the axis of rotation and to said beater element as to counterbalance the forces set up by the gyroscopic motion imparted to the latter at its connection to said member.

11. In a suction cleaner, a body, a rotatable member resiliently mounted on said body, a beater element rotatably connected to said rotatable member eccentrically of the axis of rotation thereof, means to guide the surface-contacting portion of said beater element toward and from a surface covering undergoing cleaning, said rotatable member including an eccentric mass so related to the axis of rotation and to said beater element as to counterbalance the forces set up by the gyroscopic motion imparted to the latter at its connection to said member, a pivoted brush element extended parallel to said beater element, and means connecting said brush to a gyrated portion of said beater element to reciprocate it upon the rotation of said rotatable member.

12. In a suction cleaner, a body, a reciprocating beating element, means to reciprocate said element comprising a driven shaft having an offset portion to which said element connects, and a mass carried by said offset portion having its center of mass positioned upon the opposite side of the axis of rotation of said shaft from said offset portion to counterbalance the forces set up by the rotation of said offset portion and the reciprocation of said beating element.

13. In a suction cleaner, a body, a rotatable pulley of relatively great mass, a driving belt seated on said pulley, means resiliently support-

ing said pulley for rotation upon said body about an axis eccentric to its center of mass, a non-rotatable shaft mounted in said pulley eccentrically of its axis of rotation and adapted to be gyrated upon the rotation of said mass, said shaft extending upon both sides of said pulley, and beating elements mounted upon said shaft upon both sides of said pulley.

14. In a suction cleaner, a body, a rotatable member, means substantially aligned with the axis of rotation resiliently supporting said member upon the opposite sides thereof, a non-rotatable beater element carried by said member eccentrically relative to the geometrical center of said member and exerting a gyrating force thereon in the rotation of said member, the center of mass of said rotatable member also being eccentric relative to the geometric center thereof and so arranged that the forces set up thereby in rotation substantially cancel the forces set up at said member by said beater element.

15. In a suction cleaner, a body, a rotatable member, means aligned with the axis of rotation of said member and including a movable hollow body and a resilient mounting supporting said rotatable member, a shaft eccentrically carried by said rotatable member and extended within said hollow body, and a beater element carried by said shaft and extended from said hollow body.

16. In a suction cleaner, a body, a shaft formed with aligned offset ends which are rotatably supported in said body, a non-rotatable casing enclosing the central portion of said shaft and adapted to revolve about the shaft axis of rotation upon the rotation of said shaft, a reciprocating beater element carried by said casing, and a mass carried by said shaft within said casing and having its center of mass positioned with an eccentricity relative to the axis of shaft rotation sufficient to counterbalance the gyroscopic forces of said casing and beater element.

17. The combination defined by the preceding claim in which said shaft ends are resiliently mounted and said casing ends are sealed to said body.

18. The construction defined by the second preceding claim in which a driving pulley is mounted upon one of said offset ends and provides means for the reception of a rotating torque.

19. The construction defined by the third preceding claim in which a pivoted agitating brush is connected to said casing and actuated thereby by a pivoted link carried by said casing.

DONALD G. SMELLIE.
